UNITED STATES PATENT OFFICE.

JAMES SNEEDEN, OF WICHITA, KANSAS, ASSIGNOR OF ONE-THIRD TO ALBERT RALPH MURRAY, OF WICHITA, KANSAS.

SPRAY-BURNER.

079,272.

Specification of Letters Patent. Patented Nov. 18, 1913.

Application filed October 7, 1912. Serial No. 724,369.

all whom it may concern:

Be it known that I, JAMES SNEEDEN, a citizen of the United States, residing at Wichita, in the county of Sedgewick and state of Kansas, have invented certain new and useful Improvements in Spray-Burners, which the following is a specification. My invention relates to certain improvements in burners for fuel oil or hydro-carbon burners and is designed to coöperate with a motor driven air and oil supply, and particularly an improvement on my device for the hydrocarbon furnace described in my co-pending application No. 688,108, filed April 2, 1912.

One object of the invention is to provide a burner which not only regulates the quantity of combustion mixture injected into the furnace, but also regulates the composition of that mixture whereby a smaller or greater proportion of oil is admitted to mix with the air.

Another object of the invention is to provide an automatic check in the burner, which can be set by hand for a certain desired pressure of the entering oil. If this pressure is not reached, the oil supply will be automatically shut off, until the pump is able to deliver the oil at the desired pressure. These several features of the invention adjustment of the burner is possible for varying temperatures.

The several features of the invention are shown in the accompanying drawings herein:

Figure 1 is a transverse section along line 1—1 of Fig. 2; Fig. 2 is a vertical section on line 2—2 of Fig. 1 and Fig. 3 a diammatic representation of the furnace with the burner in position.

In the different views in the drawing E presents the pipe supplying the air to the burner and F is the oil pipe leading from a suitable pump to the burner.

G is the burner casing in which is seated the main valve spindle H, which regulates the quantity of combustion mixture permitted to enter the burner nozzle through the opening C.

A passage A connecting the air pipe E with the seat of the main spindle H admits air into the burner, and an adjusting plug K, threaded in the burner casing G and

provided with a stuffing box K¹, is constructed to close this passage entirely or to open it at different degrees. This adjusting plug has an external head K² by means of which it can be regulated from the outside. On the other side of the main spindle H is symmetrically arranged a similar adjusting plug J for regulating the oil supply. This oil plug is also threaded in the burner casing G and has an external head J² and a stuffing box J¹. The oil from the oil pipe F enters the housing from the passage B where it is checked by the ball N normally closing the passage B and actuated by a spring S. The strength of this spring is regulated by means of the screw M which is also provided with a stuffing box L.

It will be noted that the air passage A¹ is considerably larger in cross section than the oil passage B¹ admitting the oil into the seat of the main spindle H. The importance of this feature is generally overlooked by designers of these kinds of burners, causing an improper kind of combustion on account of the wrong proportion of oil and air in the mixture. The areas of these passages A¹ and B¹ have been so selected that by normal running, the passages may be fully opened, that is the plugs K and J may be drawn back out of the way. When the adjusting plugs K and J have been set to give the right proportions of the mixture, the main spindle H may thereupon be set to regulate the proper degrees of heat.

The automatic closing device of the oil passage B by means of the ball N is as already described dependent on the pressure of the spring S, which pressure is intended to be varied in accordance with the different oil pressure at high or low temperature as in mild or cold weather. In practice, I regulate the pressure on the spring to the pump pressure on the oil, so that should the pump or its mechanism fail to give the desired pressure on the oil, the passage B will be automatically closed by the ball N and the spring S, and no more oil admitted into the burner.

After having once been set for the proper mixture of the oil and the air, the adjusting plugs K and J need not, under ordinary

nary circumstances be reset unless the passages in time should become clogged, when readjustment would be advisable.

I claim:

- 5 1. In a hydrocarbon burner device, in combination with a fuel mixture passage, an oil passage and an air passage in communication with said fuel mixture passage; the maximum cross sections of the oil passage and the air passage being proportioned to correspond to the quantities of oil and air entering into the fuel mixture; and said oil passage being provided with an automatic resisting valve yieldingly seated against the flow of oil through said oil passage and having means for regulating its resistance at will.
- 10 2. In a hydrocarbon burner the combination with a burner casing, a main valve spindle and a seat therefor for admitting the compression mixture to the burner, an oil pipe and an air pipe, an air passage connecting the air pipe with the seat of said main spindle, and an oil passage connecting

the oil pipe with said valve seat, an adjustable plug in said oil passage for regulating the cross section thereof; the maximum cross section of said oil passage being smaller than the maximum cross section of said air passage; of a device in said oil passage for automatically admitting fuel above a fixed minimum pressure, said device comprising a ball, a set screw and a spring abutting against said set screw and said ball; whereby said oil supply will be automatically cut off when the oil pressure is less than desired; the minimum amount of pressure being regulated through the adjustment of the compression of said spring by means of the set screw.

The foregoing specification signed at Wichita, Kansas, this 16th day of September, 1912.

JAMES SNEDDEN.

In presence of—

WALTER J. BRANT,
ARCH SHEARER.
